STAPLING APPARATUS

Joseph C. Lang, Pittsburgh, Pa., assignor to Bocjl Corporation, a corporation of Delaware

Application November 30, 1942, Serial No. 467,365

17 Claims. (Cl. 1—13)

1

This invention pertains to the art of stapling and is for an apparatus wherein the staple is of special form whereby it is reinforced against bending during driving and wherein it has an increased holding power over the conventional U-shaped staple, and is for a machine in which the staple is clinched while it is being driven without the use of any anvil under the work and without bending the legs of the staple after they have penetrated the material.

The invention is complementary to the invention disclosed in my copending application Serial No. 467,366 filed November 30, 1942, issued as U. S. Letters Patent No. 2,393,327 on Jan. 8, 1946, for Staple driving method and apparatus. Insofar as any subject matter of the present application is common to my said copending application the broad subject matter is covered in the said copending application and the present application is directed primarily to an instrument for driving a specially formed staple according, however, to the general principle disclosed in the said copending application.

The present application also is a companion application to my copending application Serial No. 467,367 filed November 30, 1942, issued as U. S. Letters Patent No. 2,380,655, on July 31, 1945, for an improvement in staples and method of stapling, wherein the specific form of staple is separately claimed.

In the latter application there is disclosed a staple having a crown which is longer than the spread between the legs of the staple. The staple has spaced parallel legs which are joined to the crown by an outwardly turned fold or lobe so that the lobes project outwardly beyond the legs of the staple. In the preferred form of staple the crown is depressed so that the undersurface of the crown occupies the same plane as the undersurface of the lobes of the staple. This form of staple has certain advantages which are clearly pointed out in the said copending application. While it has certain advantages it also presents a problem from the standpoint of driving it. The conventional U-shaped staple, when it enters the staple guide, fits into the guide, the legs being received in the staple guide which hold the staple so that it can not tilt. The legs can not bow outwardly during the driving of the staple because of their engagement with the walls of the staple guide. However, when the staple is modified to the shape shown in the latter of the two above mentioned applications, only the lobes or ears on the staple engage in the staple guides and the legs of the staple have no lateral support to pre-

2

vent them from bowing inwardly or outwardly and a special problem of guiding the staple therefor arises.

In the former of the two copending applications above mentioned, the legs of the staple pass through slots or kerfs cut into a guiding plate or member which I term a "masking" plate. These kerfs are curved away from the plane of the leg of the staple so that as the legs of the staple pass down through the kerfs the ends of the staple are deflected toward or away from each other, and as the staple progressively moves through the kerfs the succeeding portions of the legs are bent so that the legs of the staple enter the material on a curved path and this curvature is followed throughout the driving of the staple. When the staple has been completely driven it will be clinched. For use with such an operation a specially formed staple of the type referred to presents a further difficulty in that the legs of the staple must be very accurately guided into the kerfs in order for the machine to function properly.

It is a purpose of the present invention to provide a driver for specially formed staples of the type referred to in which means is provided for guiding the legs of the staple, such means being moved out of the way when the staple has been completely driven. This means assures the legs of the staple properly entering the kerfs in the masking means and it also supports the legs against buckling during the driving operation. The invention further provides means for applying a desired amount of friction to the staple to prevent it from dropping freely when it enters the staple guide so that it is pushed down by the driver instead of falling clear of the end of the driver. The present invention also provides a masking means for cooperation with the specially formed staple. The invention also provides certain other improvements, particularly in the manner of supporting the staples in the magazine prior to being driven. My invention may be readily understood by reference to the accompanying drawings, in which:

Figure 1 is a side elevation of a complete machine for closing boxes, the machine being constructed in accordance with the present invention;

Figure 2 is a longitudinal section on a larger scale than Figure 1, showing the staple feeding and driving mechanism;

Figure 3 is a fragmentary transverse section in the plane of line III—III of Figure 2;

Figure 4 is a similar section in the plane of line IV—IV of Figure 2;

Figure 5 is a fragmentary view on still a larger scale than Figure 2 with certain parts of the staple guiding mechanism being shown in elevation;

Figure 6 is a view similar to Figure 5, with a lesser portion of the machine being shown and showing the staple partially driven;

Figure 7 is a view similar to Figure 6 but with the staple completely driven;

Figure 8 is a horizontal section in the plane of line VIII—VIII of Figure 5;

Figure 9 is a detail view showing the driven staple in overlying lifts of material; and

Figure 10 is a view similar to Figure 9 wherein the legs of the staple are turned outwardly instead of inwardly.

Referring first to Figure 1 of the drawings, 2 designates a base on which is a vertical column 3. At the top of the column 3 is a cap 4 having a horizontal bracket 5 thereon. Pivotally supported on the pin 6 in the cap 4 is a lever designated generally as 7. This lever has a forwardly projecting bifurcated arm 7a and a rearwardly extending portion 7b. At the forward end of the arm 7a is the staple driving assembly, designated generally as 8 and which will be hereinafter more fully described.

On the column 3 is an adjustable support 9 which has an adjustable table 10 thereon. This table has work positioning guides 11 on its surface, these guides being set to receive the box B or other article to be stapled.

Pivotally connected to the arm 7b of the lever 7 is a downwardly extending link 12, the lower end of which is pivotally connected at 13 to a lever 14 that is pivotally mounted on the base at 15 and which has a treadle 16 at its forward end. A spring 17 serves to elevate the treadle after it has been depressed. Pressing down on the treadle 16 rocks the lever 7 to operate the staple driving unit 8 in the manner hereinafter set forth.

The general form of machine shown in Figure 1 is known to the art and so much of it as has been described forms no part of the present invention per se, the present invention being concerned with the construction of the staple driving unit, designated generally as 8. Pivotally supported on the pin 6 and extending forwardly under the arm 7a of the lever 7 is a rigid bar 18. Secured by welding or otherwise to the bar 18 are two side plates 19 which are tapered to increase in height forwardly. Supported between these two plates at the top of the forward left-hand end thereof is a block 20, having a ledge or shoulder 21 on the front thereof. The two side plates have opposed vertical grooves therein forwardly of the block 20 and coextensive with the full height of the plates 19, these grooves providing a guide for the staple driver 22. The staple driver 22 is connected at its upper end to a block 23. Carried on the block 23 is a casing 24, which extends over the front of the assembly and which has two wings that extend rearwardly over the side plates 19, these wings being designated 24a. This shell or enclosure, having a sliding fit over the front of the assembly, serves additionally to support and guide the driver 22. The block 23 has a downwardly projecting pin 25 thereon (see Figure 2) and a coil spring 26 having its upper end around this pin and its lower end surrounding an abutment 27 on the shoulder 21 yieldably resists downward movement of the driver and serves to return the driver to an elevated posi-

tion when it has been moved down relative to the block 20. The pin 25, co-operating with the abutment 27, limits the travel of the driver. For operating the driver, the bifurcated forward portion 7a of the lever 7 is provided on each arm thereof with a link 28. The upper ends of the links 28 are pivotally connected at 29 to the block 23.

In operation, the arm 18 and the forward end 7a of the lever 7 move downwardly together when the treadle 16 is depressed until the downward movement of the arm 18 is arrested. When the arm 18 can no longer move downwardly the continued downward movement of the portion 7a of the lever causes the head or block 23 to be pulled down relatively to the block 20 and thus cause a relative movement of the driver 22 along its guides. Aside from the particular construction of the side plates 19, to be hereinafter more fully described, the general arrangement of this part of the driver is more or less conventional.

According to the present invention each of the two side plates is provided on its surface with a horizontal groove, best shown in Figure 3, and designated 30. Figure 3 also shows in elevation one of the staples marked S which the present machine is designed to drive. The grooves 30 provide channels to receive the lobes or ears S' on the staples S so that the staples are suspended between the two plates by means of these lugs or ears. The side plates 19 are additionally recessed as indicated at 31 to provide a clearance space for the legs of the staple but the recesses 31 are of less depth than the grooves 30. A long row of staples may be supported between the side plates, all of the staples of the row being thus suspended by means of the ears or lobes engaging in the grooves 30. A pusher or follower, best shown in Figure 2, and designated 32, is also provided, this pusher having a cross section corresponding to the shape of the staples, and having ears which ride in the grooves 30. A long coil spring 33 has one end thereof attached to a lug 32a on the underside of the pusher. This spring extends toward the left as viewed in Figure 2, passes over a guide roller 34 near the left-hand end of the machine, this roller being shown in elevation in Figure 3, and there is a return reach of the spring that extends toward the right to a point of anchorage at 35. As shown in Figures 2 and 3, the upper reach of this spring is under the crown of the staple and between the legs of the staple while the lower reach of the spring is entirely below the legs of the staple. With this arrangement a very positive spring for moving the staples can be provided and a more desirable magazine and feed construction is secured than with conventional machines where the staples are set astraddle a supporting bar. The spring 33 of course urges the follower 32 toward the left as viewed in Figure 2, thus exerting pressure against the row of staples in the magazine.

As best shown in Figure 8, the forward portions of the lower parts of the side plates 19 are of reduced thickness, these thinner parts being designated 19a. This leaves a shoulder at 19b which forms one face of the staple guide. Mounted on the inner face of each portion 19a is a slender strip 36. The strips 36 have diagonal slots 37 therein (see Figures 2 and 5) and fixed guide pins 38 pass through these slots into the portions 19a of the side plates. A coil spring 39 attached to the top of each plate 36 and anchored to the side plate tends to yieldably urge the strips 36 upwardly while the inclination of

the slots 37 tends to cam the strips 36 inwardly or toward the right as they are pulled outwardly. However, the strips 36 can move downwardly and outwardly. The strips 36 in conjunction with the shoulders 19b provide the grooves designated 40 in Figure 8 that constitute the lower portion of the staple guide or chute. The strips 36, as best shown in Figures 2 and 5, form an abutment against which the endmost staple at the left of the mechanism engages to limit the movement of the staples toward the left. When the staple is projected forwardly so that its lugs or lobes contact the strips 36, the staple will be directly under the driver. While the lugs or lobes of the staples will be guided in the slots 40 the legs of the staple will also be engaged in the grooves 40 but the legs will be spaced inwardly from the side plates. This is best seen in Figure 4 where the staple is shown in dotted lines and where it will be seen that the legs of the staple are guided by the strips 36 but that the legs are spaced inwardly from and unsupported by the side plates 19.

The strips 36, being urged inwardly to a limited extent by the cam slots 37 and springs 39, exert a yielding frictional pressure against the staple so that it cannot fall freely down the staple guide but is frictionally held in the staple guide until the staple is actually forced downwardly by the driver.

The foregoing arrangement in which the strips 36 are used to exert pressure against the staple is a novel arrangement and is superior to mechanisms heretofore provided for frictionally engaging the staple to prevent it from dropping freely.

Pivoted to the exterior of each side plate 19 on a pivot pin 41 is a bell crank 42 having a downwardly extending arm 43 and a horizontally extending arm 44. A tension spring 45 has one end attached to the arm 44 and the other end anchored at 46 to the side plate 19. The downwardly extending arm 43 is turned inwardly at 43a and passes through a hole 47 in the side plate. Inside of this plate it extends downwardly and forwardly as indicated at 48, the terminal portion 48 being in the shape of a hoof and the hoof portion of each arm 43 projects across the staple guide. As best seen in Figure 4, this hoof is bifurcated, as indicated at 49, so that the legs of the staple, as the staple is pushed down the guide, pass through the bifurcated portion 49 of the hoofs. These hoofs serve as guides to direct the points of the staple into kerfs 50 formed in the masking plate or guide plate 51 slidably carried on the bottom of the staple driving unit and which will be hereinafter more fully described. The forwardly and downwardly inclined surface of each hoof is engaged by the crown of the staple during the downward travel of the staple, thereby camming the hoof back out of the way of the crown or bridge of the staple. Figure 5 shows the terminal or hoof 48 in its normal position, and Figure 6 shows the hoof cammed back out of the way of the crown of the staple. The spring 45, acting through the bell crank lever, serves to return the hoofs or terminals 48 to their normal position after the staple has been driven and the driver has been retracted. These hoofs or slotted terminals of the bell crank lever are important factors in guiding the specially formed staples to assure the points of the staples being directed into the slots or kerfs 50 and are also important in preventing the legs of the staple from buckling either inwardly or outward-

ly during the driving of the staple. Their significance as a lateral support for the legs is best illustrated in Figure 4.

The stapling guide or masking plate 51 which effects the bending or clinching of the legs of the staple comprises a relatively thin, flat part 51 at the bottom of the driving assembly. It has upwardly extending flanges 52 at each side thereof, these flanges embracing the lower edges of the side plates 19. Projecting out from the sides of the plates 19 are retaining pins 53, the projecting ends of which are engaged in bayonet slots 54 in the flanges 52. This arrangement enables the plate 51 to be moved back and forth the length of the slots and it also permits the member 51-52 to be removed should this be necessary for any purpose. The masking member 51 is resiliently urged toward the left as viewed in Figures 2 and 5 by means of a light metal strip 55 which is slidably retained on the outer face of each plate 19 rearwardly of the member 51. A tension spring 56 anchored to the plate at 57 and anchored to a stationary post 58 urges the plate 55 toward the left as viewed in Figure 5 to press against the end of the flange 52. When the plate 51 moves toward the right as viewed in Figure 5 it does so against the tension of the spring 56.

The plate 55 has a forwardly extending tongue portion 51' and it is into this tongue portion that the kerfs 50 are cut. As explained in my copending application Serial No. 467,366 filed November 30, 1942, issued as U. S. Letters Patent No. 2,392,327 on January 8, 1946 these kerfs are cut at a curvature such that the tops of the kerfs are separated a distance equal to the spread of the staple and the tops of the kerfs are also in the plane of the diameter of a circle whose diameter is equal to the spread of the staples. The kerfs 50 are of a width equal to the thickness of the legs. As explained in my copending application, the kerfs may be either curved inwardly or outwardly, but in either case the curvature is substantially a portion of the arc of the circle. In Figure 4 the kerfs are curved inwardly and it will be seen that as the staple is forced down the legs of the staple are progressively curved in passing through the kerfs, causing the points to penetrate and travel through the material in a curved path. On the tongue 51' between the two kerfs is an upwardly and rearwardly extending inclined tongue or cam 59 which, as shown Figure 4, has a width less than the distance between the two hoofs 49. As shown in Figure 5 this tongue 59 is in the path of the downward movement of the driver 22 and also in the path of movement of the crown of a staple being forced down the guideway by the driver. As the driving of the staple nears completion the crown of the staple engaging the cam 59 exerts a horizontal component of force, tending to move the masking or guide plate 51 toward the right as viewed in Figure 5. Consequently, by the time that the crown of the staple is down to the plane of the top of the tongue 51' the plate 51 has been cammed back to a point where the staple is clear of the part 51' and is no longer within the kerfs. This enables the crown of the staple to be forced down tightly against the work into which the staple is driven. Referring to Figure 5, the tongue 51' is in its normal position. Figure 6 shows the position of the tongue 51' at the time the staple has been partly driven and the plate 51 starts to move back, and Figure 7 shows the driver all the way down with the tongue 51' re-

tracted to be entirely clear of the staple. The ends of the bayonet slots 54 in cooperating with the pins 53 limit the movement of the masking plate toward the left while the normal range of movement toward the right is that effected by the camming action and is equal to the width of the crown of the staple. The normal range of movement is such that the pins 53 remain in the horizontal parts of the bayonet slots 54 so that the plate 51 is normally retained in position.

The operation of the machine may now be described. Assuming the magazine to have been charged with a row of staples, the endmost staple on the left as shown in Figure 2 is under the driver 22. Its further movement toward the left is blocked by the guide strips 36. When the treadle is depressed the driving unit as a whole is lowered against the surface of the box B. When the slide plate 51 contacts the surface of the box further downward movement of the stapling machine as an entire unit is arrested. In order to prevent undue pressure on the surface of the box, there is an adjustable screw 60 on the bracket 5 which forms an abutment to limit the downward movement of the lower arm assembly of the machine, this bolt contacting with the undersurface of the bar 18. Continued downward movement of the treadle, however, then causes the driver 22 to move relatively to the lower part of the assembly and the driver engages the staple which is in the guide and forces it downwardly. The staple is retarded from falling by the friction exerted through the two guide strips 36. The legs of the staple first pass through the bifurcated swinging guides or hoof-like guides 48 and by these guides they are accurately aligned with the kerfs 50 in the tongue 51' of the guide plate. With the continued downward movement of the staple the legs are forced through the kerfs 50, as best shown in Figure 4, and this directs the points of the staples into the material in a curved path. As the legs of the staple continue to move downwardly successive portions of the staple are engaged and curved so that the legs, instead of traveling in a vertical path, travel in the arc of a circle. This is fully explained in my copending application Serial No. 467,366 filed November 30, 1942, issued as U. S. Letters Patent No. 2,392,327 on January 8, 1946. When the staple has been partially driven into the material the crown of the staple will engage the inclined surface 59 on the guide plate 51 so as to cam the guide plate 51 toward the right as viewed in Figures 5 and 6. When the crown of the staple reaches the level of the top of the tongue 51' the tongue 51' will be entirely clear of the staple and the driver will press the staple home against the top flap or lift of the box as illustrated in either Figures 9 or 10. In Figure 9 the staple, designated 61, has the crown 62 flush against the top lift B¹ of the box while the curved legs 63 are clinched in the lower lift B² of the box. In Figure 9 the legs are curved inwardly so that in clinching they meet and overlap. In Figure 10, in which corresponding reference numerals have been used, the kerfs are curved in so as to deflect the legs outwardly. This increases the spread over which the holding power of the staple is exerted. Either the type of clinching shown in Figure 9 or Figure 10 may be used. Because of the special form of the

staple the downward force of the driver is exerted against the crown squarely over the tops of the legs of the staple and in line with the legs. This enables the staple to be driven into very dense material such as hard fiber board and to satisfactorily clinch rather than to squash down as might be expected. It will be noted that a particularly important feature of this application is the provision of hoofs or guides 48 by means of which the inner and outer surfaces of the legs of the staple are supported between the crown and the tongue 51' of the guide plate to prevent the legs from buckling in the initial part of the drive. These hoofs or guides 48 compensate for the absence of the lateral support which the side walls of the staple guide provide for the conventional U-shaped staple. As above indicated, this special form of staple can be more satisfactorily driven into hard material due to the legs being set inwardly from the guides because the pressure is applied by the driver to the staple directly over the legs and the lobes of the staple form a reinforcement to make the staple stronger than the conventional U-shaped staple. Also, as explained in my copending application Serial No. 467,367 filed November 30, 1942, issued as U. S. Letters Patent No. 2,380,655, on July 31, 1945 the special form of staple has an added holding power over the conventional U-shaped staple. Another important function of the guides or hoofs 48 is the guiding of the legs of the staple into the kerfs 50.

In the present application, the guiding plate 51 is cammed back by the downward movement of the staple but it will be understood that this is only one way of retracting the guide plate and, if desired, the linkage system disclosed in my copending application Serial No. 467,366 filed November 30, 1942, issued as U. S. Letters Patent No. 2,392,327 on Jan. 8, 1946, may be used or that any other appropriate mechanism may be employed for this purpose.

Since the driver is designed for use with a specially formed staple it would not operate if the conventional U-shaped staple were inserted in the magazine. In order to prevent a user from jamming the machine by attempting to use staples other than the ones particularly intended for it, the magazine is designed to support the staples by suspending them from the lobes rather than the usual construction of resting the crowns of the staples on a bar along which the staples slide. There would be no way of supporting conventional staples in the machine and therefore the operator could not jam the machine by attempting to use staples which could not be handled by the driving mechanism. Also, as best seen in Figures 2 and 3, metal strips 19 are secured to the inner faces of plates 18 and the lower edges of these plates engage the staples S to aid in keeping them in place, and these strips would prevent the use of staples in the magazine in which the crown between the lobes is not depressed.

It should be further pointed out that the present invention provides an arrangement for guiding a staple in which each leg of the staple is completely boxed in on four sides as it moves down the staple guide or chute, which in itself is a novel arrangement. The two sides of the bifurcated terminals 48, that is the hoof-like members, engage the two side faces of each leg, the inner surface of this bifurcated terminal guides one edge of the leg that passes therethrough and

the other edge is engaged by the movable guide strips 36.

I claim:

1. A stapling machine of the class described having a reciprocable driver, means forming a delivery chute along which the driver is movable, guide means normally projecting into the delivery chute extending across the path of the driver and having slots therein positioned to engage and support the legs of the staple moving along the chute, said guide means being movable out of staple-engaging position.

2. A stapling machine of the class described having a reciprocable driver, means forming a delivery chute along which the driver is movable, guide means normally projecting into the delivery chute extending across the path of the driver and having slots therein positioned to engage and support the legs of the staple moving along the chute, said guide means being movable out of staple-engaging position, said guide means having cam surfaces thereon to be engaged by the crown of a staple being driven for moving the guide means clear of the staple.

3. A stapling machine of the class described having a reciprocable driver, means forming a delivery chute along which the driver is movable, guide means projecting into the delivery chute normally extending across the path of the driver and having slots therein through which the legs of a staple moving down the chute will pass, means resiliently urging the guide means into normal position, and a surface on the guide means for engagement by the staple being driven or the driver by means of which the guide means is moved clear of the staple after the staple has been partially driven.

4. A stapling machine of the class described having means providing a staple delivery chute, a driver for moving the staples along the chute and forcing them into the material into which the staple is to be driven, and guide means normally extending into the chute in the path of movement of the staple, said guide means having open-ended slots therein the width substantially equal to the width of the staple being driven and through which the legs of the staple pass in being driven, said slots supporting the inner and outer faces of the legs of the staple, and means for retracting the guide means after the staple has been partially driven.

5. A stapling machine for driving staples of the type wherein the crown projects at each end beyond the legs of the staple, said machine comprising a driver, a guide chute along which the staples are moved by the driver and in which the ends of the crown of the staple being driven is guided, and movable guide means spaced inwardly from the sides of the chute for engaging and supporting the inner and outer surfaces of the legs of the staple while they are passing down said chute, said guide means being movable through the operation of the driving of the staple to a position clear of the legs.

6. A stapling machine for driving staples of the type wherein the crown projects at each end beyond the legs of the staple, said machine comprising a driver, a guide chute along which the staples are moved by the driver and in which the ends of the crown of the staple being driven is guided, and movable guide means spaced inwardly from the sides of the chute for engaging and supporting the inner and outer surfaces of the legs of the staple while they are passing down said chute, said guide means being movable

through the operation of the driving of the staple to a position clear of the legs, said guide means having cam surfaces thereon by means of which said means are engaged by the crown of a staple being driven and forced out of engagement with the staple after the staple has traveled a predetermined distance along the guide chute.

7. A stapling machine of the class described having a movable driver, means forming a staple delivery chute along which the driver is movable for driving a staple, levers having free offset bifurcated terminal portions projecting into the chute with the bifurcations so positioned that the legs of a staple passing down the chute will 15 pass through the bifurcations and the inner and outer faces of the legs of the staple will be supported thereby, said levers being pivotally supported on the stapling machine, the terminal portions of the levers being shaped to provide 20 cam surfaces which are engaged by the crown of the staple being driven for moving the said terminal portions clear of the legs of the staple, and resilient means for urging the levers to normal position after the terminals thereof have been 25 displaced.

8. A stapling machine of the class described having a reciprocable driver, means forming a delivery chute along which the driver is movable, guide means normally projecting into the delivery chute extending across the path of the driver and having slots therein to engage and support the legs of the staple moving along the chute, said guide means being movable out of staple-engaging position, there being strips forming a 30 portion of the guide chute at each side thereof, said strips being diagonally movable with respect to the face of the driver, and means for resiliently urging the strips upwardly and inwardly toward the driver for frictionally exerting pressure against staples in the chute.

9. A stapling machine of the class described having a driver, a supporting structure on which the driver is movable, means on the supporting structure providing a staple delivery chute along 45 which the driver moves, masking means on the supporting structure movable in a plane at right angles to the direction in which a staple moves and being driven, said masking means having open-ended slots therein positioned to receive the legs of the staple being driven, said slots being curved in the direction of travel of the staple for bending the legs, means for withdrawing the masking means from engagement with the staple after the staple has been partially driven, and 50 a staple guiding means in the chute above the masking means having straight slots therein for supporting the inner and outer faces of the legs of the staple passing down the chute, said guiding means also being movable out of staple engaging position.

10. A stapling machine of the class described comprising a supporting structure, a reciprocable driver on the supporting structure, means in the supporting structure providing a chute along 55 which staples being driven are moved by the driver, means for delivering staples to the chute, masking means on the bottom of the supporting structure at the end of the staple delivery chute having slots therein normally positioned to receive the free end of the legs of the staple as the staple is being driven, said slots being curved to bend the legs of the staple as the staple passes through the masking means, means for withdrawing the masking means from engagement 70 with the staple after the staple has been driven 75

11

to a predetermined extent, and guide means normally projecting into the chute across the path of travel of the driver and having guide slots therein for guiding the legs of the staple into the slots in the mask and for supporting the inner and outer faces of the staple against buckling, said guide means being movable to a position clear of the staple.

11. A stapling machine of the class described comprising a supporting structure, a reciprocable driver on the supporting structure, means in the supporting structure providing a chute along which staples being driven are moved by the driver, means for delivering staples to the chute, masking means on the bottom of the supporting structure at the end of the staple delivery chute having slots therein normally positioned to receive the free end of the legs of the staple as the staple is being driven, said slots being curved to bend the legs of the staple as the staple passes through the masking means, means for withdrawing the masking means from engagement with the staple after the staple has been driven to a predetermined extent, and guide means normally projecting into the chute across the path of travel of the driver and having guide slots therein for guiding the legs of the staple into the slots in the mask and for supporting the inner and outer faces of the staple against buckling, said guide means being movable to a position clear of the staple, the guiding means having cam surfaces thereon positioned to be engaged by the crown of a staple being driven for moving the guide means out of engagement with the staple as the crown moves down the chute.

12. The combination in a stapling machine of the class described having a staple chute and driver, of bifurcated means for engaging and guiding the inner and outer faces and one edge of the legs of a staple moving down said chute, said means being movable from a position to engage and guide the staple to a position clear thereof.

13. The combination in a stapling machine of the class described having a staple chute and driver, of bifurcated means for engaging and guiding the inner and outer faces and one edge of the legs of a staple moving down said chute, said means being arcuately movable from a position to engage and guide the staple to a position clear thereof.

14. The combination in a stapling machine of the class described having a staple chute and driver, of bifurcated means for engaging and guiding the inner and outer faces and one edge of the legs of a staple moving down said chute, said means being movable from a position to en-

12

gage and guide the staple to a position clear thereof, and means yieldably pressing against the other edges of said staple.

15. A fastener-applying implement comprising means for driving U-shaped staples into the work, a retractable deflector-element mounted on the implement and provided with means engageable with the legs of a staple to deflect them inwardly toward each other during their penetration into the work, and means engageable by the crossbar of the staple to retract the deflector-element at the end of the driving operation.

16. A fastener-applying implement comprising means for driving U-shaped staples into the work, a retractable deflector-element mounted on the implement and provided with means engageable with the legs of a staple to deflect them inwardly toward each other as they are driven into the work, and means operable by the driving of a staple to retract the deflector-element out of range of the driving means.

17. A fastener-applying implement comprising means for driving U-shaped staples into the work, a yieldable deflector-element mounted on the implement and provided with means engageable with the legs of a staple to deflect them inwardly toward each other as they are driven into the work, and means integrally formed on said deflector-element and operable by the driving of a staple to yieldably move the deflector-element out of range of the driving means.

Certificate of Correction

Patent No. 2,440,479.

April 27, 1948.

JOSEPH C. LANG

It is hereby certified that errors appear in the printed specification of the above numbered patent requiring correction as follows: Column 1, line 14, for the patent number "2,393,327" read 2,392,327; column 12, line 51, list of references cited, under the heading "UNITED STATES PATENTS" for the date "Dec. 4, 1936" read Dec. 4, 1934; and that the said Letters Patent should be read with these corrections therein that the same may conform to the record of the case in the Patent Office.

Signed and sealed this 15th day of June, A. D. 1948.
